UNITED STATES PATENT OFFICE

HENRY F. MERRIAM, OF WEST ORANGE, NEW JERSEY, ASSIGNOR TO GENERAL CHEMICAL COMPANY, OF NEW YORK, N. Y., A CORPORATION OF NEW YORK

APPARATUS FOR COOLING FLUIDS

Application filed November 9, 1926. Serial No. 147,245.

This invention relates to a process of transferring heat from one fluid to another and particularly to the cooling of one gas by another.

5 In many chemical processes it becomes necessary to cool gases containing corrosive vapors or considerable amounts of moisture. If the cooling operation is not carefully controlled these vapors will condense out of the 10 gas stream in the form of a liquid and corrode the equipment. For example, in the contact process for the manufacture of sulfuric acid, particularly where the source of sulfur is brimstone, as in the U. S. patent to Merr- 15 riam 1,384,566, it becomes necessary to abstract considerable quantities of heat from sulfurous gases containing moisture and some sulfur trioxide. The most common procedure for cooling these gases is to pass them 20 through heat transmitters constructed of steel through which air or other cooling fluid is circulated as the cooling medium. If the temperature of the sulfurous gases is lowered at any point in the heat transmitter below 25 that temperature at which the contained sulfuric acid begins to condense, serious corrosion of the transmitter tubes will result and necessitate expensive repairs and replacement of the corroded apparatus. This con- 30 densation temperature is frequently rather high, being for example around 400° F. for a gas containing about 0.5 gram of moisture per cu. ft., which corresponds roughly to the gas produced when burning brimstone with 35 undried air having a high humidity. If localized cooling occurs in the heat transmitter at the point where the cooling medium initially contacts with the heat transmitter tubes, such that the temperature of the tubes 40 falls below the temperature given in the above example, condensation of sulfuric acid will occur and result in corrosion at this point.

Various methods have been proposed for 45 preventing this condensation, for example, by using preheated steam having a temperature above 400° F. as the cooling medium, as shown in the U. S. patent to Bezanson 1,542, 488. Such methods require the installation 50 of expensive apparatus and are objectionable

for this reason. It is an object of my invention to overcome the disadvantages above given in a simple manner requiring but slight modification of present types of heat transfer apparatus.

A further object of my invention is the provision of an improved process of and apparatus for cooling a fluid to a predetermined temperature by means of a cooling medium having an initial temperature below such 60 predetermined temperature, whereby increased heat transfer efficiency is obtained.

I have illustrated an apparatus embodying my invention in the accompanying drawings, in which:

Fig. 1 represents an elevation view in cross-section through this apparatus, and

Fig. 2 represents a cross-section view upon the line 2—2 of Fig. 1.

The apparatus as shown comprises a steel 70 container shell 1 having end walls 2 and 3 and tube sheets 4 and 5 at each end thereof. The tube sheets 4 and 5 form in conjunction with the end walls 2 and 3 a header or distributing section at each end of the container for 75 the entering and leaving fluid being cooled. These headers are provided with an outlet 6 and inlet 7, respectively. Secured in the tube sheets and passing through the shell are a plurality of heat transmitter tubes 8, 80 forming a tube nest through which the fluid to be cooled is passed. The shell 1 and tube sheets 4 and 5 form a container through which the cooling fluid is circulated to exert a cooling action upon the outer surfaces of 85 the transmitter tubes 8. The container is provided at its lower end with a plurality of openings 9 spaced uniformly around the circumference of the container and through which the cooling fluid enters. The open- 90 ings 9 communicate with an annular chamber surrounding the container formed by the bustle or distributing pipe 10. The cooling fluid enters the bustle pipe from the supply pipe 11; the flow being controlled by the 95 butterfly valve 12, and leaves the container through the outlet 13. In this same end of the container is also placed a partition or wall 14 forming with the tube sheet 5 a compartment connected with the outlet 13. 100

- This wall 14 is also formed as a tube sheet and has tubular baffles 15 attached thereto and placed concentrically of the tubes 8. The baffles 15 extend from the wall 14 in the direction of the tube sheet 4, thus forming a passageway 16 between the tubes 8 and baffles 15 opening into the compartment between wall 14 and tube sheet 5 at one end and the interior of the container at the other end.
- As above stated, the fluid to be cooled passes through the tubes 8 in the direction indicated by the arrows. The cooling fluid, which will ordinarily be air, enters from the supply pipe 11 into the bustle pipe 10, and from here is uniformly distributed through openings 9 into the container and caused to circulate around the baffles 15 and then flow upwardly through the container as indicated by the arrows. The baffles 15 will be heated by transfer of heat from the hot gases passing through the tubes 8, and this heat will of course be transferred to the cooling fluid during its passage along the baffles 15 through the passageway formed by the baffles and container wall 1. The temperature of the cooling fluid will thus be raised by the time it reaches the upper end of the baffles 15 and before it initially contacts with the outer surfaces of the heat transerrer tubes 8. The thus preheated cooling fluid then passes downwardly through the passageways 16 formed by the baffles 15 and tubes 8, passes into the compartment between wall 14 and tube sheet 5, and thence to outlet 13. During the passage of the cooling fluid through the passageways 16 it will of course exert a cooling action on the tubes 4 and thus cool the hot gases to whatever temperature is desired.
- I have illustrated the streams of fluid to be cooled and cooling fluid as passing in counter-current flow. Likewise, the streams of cooling fluid upon opposite sides of baffles 15 pass in counter-current flow. This arrangement results in greater heat transfer efficiency than would co-current flow and is preferred for this reason.
- The distance between the tube sheets 4 and 5 and consequently the length of the baffles 15 will be made sufficiently great to bring about a general overall uniformity of temperature conditions in the cooling fluid by the time it reaches the upper end of the baffles and contacts with the transerrer tubes.
- For operation with air as a cooling fluid upon hot sulfurous gases in a contact sulfuric acid system, and using an apparatus of the general design shown in the drawing, I have obtained satisfactory operation with an apparatus in which the length of the baffles was approximately equal to the diameter of the container shell. However, it should be understood that the dimensions of the apparatus will vary with particular operating conditions and my invention is not

limited to the particular embodiment illustrated in the drawing.

It will be seen that in accordance with my invention a transfer of heat takes place from the hot gases to be cooled to the streams of cooling fluid passing through the passageways 16, and simultaneously with this there is a transfer of heat from these streams to the streams of cooling fluid passing upwardly around the baffles 15. The amount of heat in the cooling fluid in the passageways 16 is thus being constantly lowered by the cooling action of the entering cooling fluid passing upwardly outside of the baffles 15. The temperature of the cooling fluid in passageway 16 is thus much lower, particularly in the lower portion of the passageway, than if this simultaneous supplemental cooling action were not taking place. This of course results in a much greater heat transfer efficiency than if a cooling medium preheated to the temperature obtaining at the entrance to the passageways 16 were alone used, and moreover permits the use of air at atmospheric temperature to be used without necessitating the employment of elaborate preheating apparatus.

It will be clear that by varying the amount of entering cooling fluid by means of the valve 12 the temperature to which the cooling fluid will be preheated by the time it initially contacts with the tubes 8 may be varied. If the quantity of cooling fluid is reduced, it will of course be preheated to a higher temperature, and likewise if the quantity is increased the amount of preheating will be reduced. The system is thus flexible and capable of close control to maintain any desired temperature in the cooling fluid at its point of initial contact with heat transerrer walls having the fluid to be cooled in contact with the opposite surfaces thereof. Localized cooling of the heat transerrer surfaces is thus avoided and the objectionable condensation of corrosive liquids effectively prevented.

I desire it to be understood that my invention is not confined exclusively to the cooling of gases but may be applied advantageously to any fluid where it is desired to maintain such fluid above a predetermined temperature. For example, the invention might be advantageously applied to the cooling of concentrated salt solutions, with which, if the temperature of the solution in the upper portions of the tubes 8 were allowed to fall below a certain point, crystallizing might commence upon the surfaces of the tubes and in a short time clog them and prevent the flow of liquid therethrough. By means of my invention the tubes 8 may be maintained above the crystallizing temperature and this difficulty overcome.

I claim:

1. In a heat transerrer, the combination

of a nest of tubes open for the passage of a fluid to be cooled, baffle tubes surrounding and spaced from the individual tubes of the tube nest and forming passageways therewith, 5 means for passing a stream of cooling fluid over the outer surfaces of the baffle tubes and then through the passageways between the baffle tubes and the tubes of the tube nest, and an adjustable valve controlling the flow 10 of the cooling fluid and set to admit an amount of cooling fluid which will produce a predetermined temperature condition in the cooling fluid at the point where such cooling fluid first comes into direct contact 15 with the tubes constituting the tube nest.

2. In a heat transerrer, a container, a nest of tubes extending through said container and open for the passage of a fluid to be cooled, an admission port to the interior of 20 the container, auxiliary baffle tubes of larger diameter surrounding the individual tubes of the tube nest and spaced therefrom, an outlet port from the container, said ports, baffle tubes, and container being constructed and 25 arranged to cause the entering cooling fluid to first contact with the outer surfaces of the baffle tubes, then to pass through the passageways between the tubes of the tube nest and the baffle tubes, and then to discharge through 30 the outlet port, and an adjustable valve controlling the flow of the cooling medium and set to admit an amount of cooling fluid which will produce a predetermined temperature condition in the cooling fluid at the point 35 where such cooling fluid first comes into direct contact with the tubes constituting the tube nest.

3. In a heat transerrer, the combination 40 of a nest of tubes open for the passage of a fluid to be cooled, impervious tube sheets to support opposite end portions of the tubes of the tube nest, auxiliary tubes of larger diameter surrounding individual tubes of the tube nest and spaced between the said tube sheets, 45 an additional tube sheet for supporting in position said auxiliary tubes, said additional tube sheet being spaced from one of the tube sheets of the tube nest to form therewith an outlet passage for cooling fluid, an admission 50 port to the interior of the tube nest space arranged to admit a cooling fluid near those ends of the auxiliary tubes which are supported by said additional tube sheet, impervious walls for preventing the escape of cooling 55 fluid from the tube nest space except through the annular spaces between the tubes of the tube nest and along the inner surfaces of the auxiliary tubes to the ends of the latter adjacent their supporting tube sheet, and 60 an adjustable valve controlling the flow of the cooling medium into the tube nest space and adapted to be set to admit an amount of cooling fluid which will produce a predetermined temperature condition in the cooling 65 fluid within the tube nest space at the point

where such cooling fluid first comes into direct contact with the tubes constituting the tube nest.

4. In a heat transerrer, the combination 70 of a nest of tubes open for the passage of a fluid to be cooled, impervious headers to support opposite end portions of the tubes of the tube nest, auxiliary tubes of larger diameter and surrounding individual tubes of the tube nest and open at their tops and bottoms 75 between the headers of the tube nest, an admission port to the interior of the tube nest space between its headers arranged to admit a cooling fluid near that part of the auxiliary tubes which is adjacent to the inlet end of the 80 hot fluid entering the tubes constituting the tube nest, means for preventing the escape of cooling fluid from the tube nest space except through the annular spaces between the tubes of the tube nest and along the inner 85 surfaces of the auxiliary tubes to that part of the latter where they are most closely adjacent to the entrance end of the hot fluid to the tubes of the tube nest, a passage for the escape of cooling fluid from between the 90 headers of the tube nest and an adjustable valve controlling the flow of the cooling medium into the tube nest space and adapted to be set to admit an amount of cooling fluid which will produce a predetermined temperature 95 condition in the cooling fluid within the tube nest space at the point where such cooling fluid first comes into direct contact with the tubes constituting the tube nest.

In testimony whereof, I affix my signature. 100
HENRY F. MERRIAM.
